UNITED STATES PATENT OFFICE

137,807

DESIGN FOR A JEWELRY BOX OR SIMILAR ARTICLE

Richard M. Dugdale, Dedham, Mass., assignor to Farrington Manufacturing Company, Jamaica
Plain, Mass., a corporation of Massachusetts

Application March 10, 1944, Serial No. 112,841

Term of patent 14 years

(Cl. D80—5)

To all whom it may concern:

Be it known that I, Richard M. Dugdale, a citizen of the United States of America, residing in Dedham, in the county of Norfolk and Commonwealth of Massachusetts, have invented a new, original, and ornamental Design for a Jewelry Box or Similar Article, of which the following is a specification, reference being had to the accompanying drawing, forming a part thereof.

Fig. 1 is a top plan view of a jewelry box or similar article embodying my new design; and
Fig. 2 is a side elevational view thereof.

I claim:

The ornamental design for a jewelry box or similar article, substantially as shown.

RICHARD M. DUGDALE.
